UNITED STATES PATENT OFFICE

2,514,666

FURNACE

Victor J. Nelson, Burbank, Calif., assignor to Nelson Inclined Furnace Company, Glendale, Calif.

Application November 6, 1944, Serial No. 562,233

3 Claims. (Cl. 263—40)

1

My invention relates to a furnace, and in particular to a furnace designed for the calcination, roasting or heat treating of ores or minerals. While my present furnace is primarily intended for calcination or burning of limestone, gypsum, keen cement, and cinnabar, the latter to produce mercury, it is to be understood that the furnace is also useful in connection with practically all types of ores or minerals.

An object of the invention is to provide means to prevent arching of material in the furnace.

Another object is to provide efficient, effective means for the discharge of controlled amounts of calcined material from the furnace.

A further object is to provide means for extracting a maximum amount of B. t. u.'s from the heated material in the furnace for the calcining of the fresh material introduced therein.

My invention also has for its objects to provide such means that are positive in operation, convenient in use, easily installed in a working position and easily dismantled therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a longitudinal section through a furnace embodying the foregoing features, shown built upon a hillside.

Fig. 2 is an enlarged transverse section taken on the line 2—2 of Fig. 1.

Fig. 3 is an exterior view of the lower end of my said furnace.

Fig. 4 is a broken transverse section through discharging means embodied herein.

Fig. 5 is a broken elevation, partly in section, looking in the direction of the arrows 5 of Fig. 4.

Fig. 6 is a front elevational view of my furnace looking in the direction of the arrow 6 of Fig. 1.

Fig. 7 is an enlarged, broken section, taken on the line 7—7 of Fig. 6.

Fig. 8 is an enlarged, transverse section taken on the line 8—8 of Fig. 1.

Fig. 9 is a perspective view of operating mechanism comprised in my furnace.

Referring more in detail to the drawings, the

reference number 10 indicates a hillside upon which my present furnace is preferably, though not necessarily, built. At the upper end of my furnace, I provide a hopper 12 for receiving crushed ore. The hopper preferably has a smooth-finish, concrete floor 9 in which are embedded downwardly inclined conduits 8 at the sides thereof. A screening grid 13 is arranged at the top of the hopper 12 to prevent the entrance into the hopper of over-size material. The hopper is preferably arranged at about a forty-five degree angle on the hillside. A shaft 14, journaled in the hopper, has an operating lever 15 carried thereon. Also fastened on the shaft 14 are lever arms 16, shown in Fig. 9, for reciprocating stoker or agitator rods 17 disposed within the conduits 8 and extending downwardly in the furnace.

An angle iron 18 at the lower end of the hopper 12, and spaced from the bottom of the hopper, regulates the size of the outlet from the hopper and thereby regulates the amount of material discharging from the hopper. From the hopper 12 the crushed ore is introduced into the furnace 19 downwardly along the fire-brick floor 20 thereof. The stoker rods 17 lie loosely along the downwardly inclined floor 20 of the combustion chamber 21, at the sides of such chamber. The stoker rods extend almost the full length of the combustion chamber.

The ceiling 22 of the combustion chamber 21 tapers from the larger, lower end 23 to the smaller, upper end 24, to provide an upwardly tapering combustion chamber. A safety and inspection door 25 is arranged in the ceiling or roof 22 of the furnace. My combustion chamber 21 is preferably arranged at approximately a thirty-five degree angle on the hillside. While this appears to be an optimum angle, it is to be understood that other angles may be employed for certain purposes.

The floor 20 is a false floor. That is to say, it is spaced from still another floor 26 to provide a passage 27 for the gases of combustion to pass downwardly under the floor 20 almost to its full length from lateral inlet ports 28 at the upper end of the passage to lateral outlet ports 29 near the lower end of the passage 27.

Downward flues 30 within the side walls 31 of the furnace, connect lateral ports 32 in the combustion chamber 21 with the ports 28 leading into the underneath passage 27. The lower ports 29 connect with stack sections 33 which join in a single pipe 34 leading to a suction blower 60.

Driving mechanism for the reciprocating rod 17 comprises a variable speed motor 35 and a belt-driven pulley 36. A link 37 having a driving connection with the pulley 36 is pivotally connected with a rod 38 that reciprocates in a pipe 39. The upper end of the rod 38 is in turn pivotally connected with a link 40 that is connected with the lever 15. A handle 41 is provided at the upper end of the lever 15 for manual operation, if desired, although in ordinary operation the above-described driving connection is utilized.

The shaft 42 of the pulley 36 carries a pinion 43 which in turn drives a larger gear 44 on a shaft 45 of a discharging means 46 for calcined ore from the furnace. Ore in the furnace is indicated at 47. A pivoted flap 48 normally blocks the downward flow of the ore 47 from the combustion chamber. The flap 48 is counterbalanced at 49 (see Fig. 4) to tend to maintain the flap in an ore blocking position.

The discharging means 46 comprises a series of pockets or bins 50 around the periphery thereof. Partitions 51 separate the bins from each other. Rollers 52 engage the lower face of the flap 48 and support same, in order to provide positive means for holding back the ore flow from the furnace until it is desired to discharge same. The discharging means 46, rotated in a clockwise direction, as shown in Fig. 4, admit calcined ore from the furnace into successive pockets 50 and then discharge the ore into a conduit 53 leading to a receiver or bin (not shown).

The means for supplying combustion for calcining the ore comprises an oil supply line 54 and a pressure supply line 55. The pressure is preferably steam, but for certain uses, compressed air may be used as the pressure supplying medium, and oil is preferred, although for certain uses, gas may be employed. It will be noticed in Fig. 7 that the steam is admitted into a mixing jacket 56 behind the outlet 57 of the oil line, with regard to the direction of the flow of the oil as shown by the arrow in the pipe 54 in Fig. 7. By this arrangement, the oil is pre-heated by mixing it with the steam. Due to the steam pressure, the oil is atomized in the jacket 56 and mixed with the steam, providing a satisfactory combustible fuel. The burners for the mixture are shown at 58, projecting into the furnace at the lower end. Suitable valves are provided as suggested in Figs. 1 and 6, for regulating the flow of the combustible media.

In the operation of my present device, the upwardly tapering combustion space 21 gradually and increasingly reduces the size of the combustion space over the ore so as to confine the heat more as its effect is being spent over the ore. In other words, as the combustion space extends farther away from the burners, it is smaller in cross-sectional area.

The ore emptied into the hopper 12 through the screen 13 is fed into the furnace in regulated quantities by the gate-piece 18. Heat admitted at the lower end of the combustion chamber 21 travels upward therein, and at the upper end passes out through the ports 32, down through the flues 30, through the ports 28, and downwardly beneath the furnace floor 20 to the outlet ports 29 and therethrough and upward into the stack sections 33 under the influence of the suction blower 60.

Oxygen is admitted into the opening 61 just above the ore at the lower end of the furnace. The reciprocation of the agitator rod 17 prevents

the material from arching or building over, which would cause the ore to back up in the furnace. The reciprocation is effected by the driving means hereinbefore described.

5 The discharging means shown partly in Fig. 4, provides for the discharge of measured quantities of material. The speed of discharge may be regulated by the variable speed motor. For certain uses, the motor may be eliminated and the weight 10 of the ore rotate the discharging means 46 by gravity, due to the ore in the buckets 50 on the descending side of the discharging means. In any event, the discharge is automatic.

15 My present furnace is so designed that it may be operated very economically, since the maximum of heat is removed before the products of combustion are discharged into the stack 34, by the return arrangement of passages for the gases of combustion.

20 From carbon dioxide gases discharged from the blower 60, Dry Ice is manufactured. It should also be understood that the present device may be employed for burning brick or tile by feeding 25 same through the present furnace in the manner described in connection with the material 47, so that the furnace acts as a kiln.

While I have illustrated and described what I now regard as the preferred embodiment of my 30 invention, the construction is, of course, subject to modifications without departing from the spirit and scope of my invention. I, therefore, do not wish to restrict myself to the particular form of construction illustrated and described, but desire 35 to avail myself of all modifications that may fall within the scope of the appended claims.

Having thus described my invention, what I claim and desire to secure by Letters Patent is:

40 1. A furnace construction comprising an elongated enclosure formed to have an inclined bottom, an inclined ceiling spaced above the bottom, side walls connecting the bottom and the ceiling, and an inclined material-conducting floor for material moving in a direction toward the lower end 45 of the enclosure and intermediate the bottom and the ceiling to divide said enclosure into an inclined combustion chamber between the ceiling and the floor and an inclined heat-conducting passage between the floor and the bottom, said 50 side walls having flues therein connecting the upper ends of the combustion chamber and passage and the side walls also having outlet ports communicating the lower end of said passage with the outside of the enclosure; and a burner 55 in the lower end of the combustion chamber to generate heated gases that flow upwardly in the combustion chamber to heat the downwardly moving material on the inclined floor, then pass through said flues into said passage and downwardly in said passage to heat the inclined floor 60 from the bottom, and finally emerge from the mentioned ports.

65 2. The combination with a furnace according to claim 1 of means controlling discharge of material from the lower end of the inclined floor and comprising a pivoted element in the path of movement of said material and displaceable on its pivot by the weight of said material to allow movement of material therebeyond, and a continuously driven, rotary, material-receiving member directly engaged with said element to move the latter alternately between material-flow-arresting and material-flow-permitting positions.

70 3. The combination with a furnace according to claim 1 of means controlling discharge of

material from the lower end of the inclined floor and comprising a pivoted element in the path of movement of said material and displaceable on its pivot by the weight of said material to allow movement of material therebeyond, and a continuously driven, rotary, material-receiving member directly engaged with said element to move the latter alternately between material-flow-arresting and material-flow-permitting positions, said rotary material-receiving member comprising radial partitions defining pockets to successively receive material and discharge the same, the mentioned element having successive engagement with the outer edges of said partitions.

VICTOR J. NELSON.
